UNITED STATES PATENT OFFICE.

EDWARD H. DAHLKE, OF BONNE TERRE, AND MONTIE L. SINCLAIR, OF FRANKCLAY,
MISSOURI.

SWITCH.

1,253,158.

Specification of Letters Patent.

Patented Jan. 8, 1918.

Application filed August 31, 1915. Serial No. 48,273.

To all whom it may concern:

Be it known that we, EDWARD H. DAHLKE and MONTIE L. SINCLAIR, citizens of the United States, residing at Bonne Terre and 5 Frankclay, in the county of St. Francois and State of Missouri, have invented new and useful Improvements in Switches, of which the following is a specification.

The present invention relates to improvements in railway construction.

In carrying out our invention it is our purpose to provide a switch between the main and side lines which shall be operated by mechanism arranged upon an engine to move 15 the switch to, say, open the same to the main line to close the switch to the siding, and wherein, after the train has passed the switch, will return the same to its initial position.

20 We also aim to provide a switch which is operated by mechanism connected with a train with a signal device actuated by the bridle rod or an element connected with the bridle rod so that the engineer of an approaching train will be warned or can readily ascertain the position of the switch, and thus be in a position to operate the switch operating mechanism if necessary.

It is a further object of the invention to 30 provide switch throwing means which may be automatically actuated by mechanism upon a train or which, if desired, may be operated by an approaching train so as not to necessitate the stopping of the train and the 35 inconvenience of one of the train hands leaving the same to actuate the switch, but which may be also operated by hand if desired, and further wherein the hand operating mechanism will not interfere with the automatic or train operating mechanism.

A further object of the invention is to provide a construction of this character which shall be extremely simple, easily and quickly applied, cheap to manufacture, and which 45 shall be positive and sure in operation.

With the above and other objects in view, the improvement resides in the construction, combination and arrangement of parts set forth in the following specification and falling within the scope of the appended claims.

In the drawings:

Figure 1 is a plan view illustrating the arrangement of parts when the switch is open

to the main line and showing the arrangement of the tripping mechanism upon an engine for actuating the switch to close the main line and open the siding,

55 Fig. 2 is a similar view illustrating the position of the train after the same has run on the siding and actuated the tripping mechanism for returning the switch to its initial position to clear the main line,

60 Fig. 3 is a plan view showing the arrangement of parts when the switch is closed to the siding,

65 Fig. 4 is a transverse sectional view approximately on the line 4—4 of Fig. 3,

Fig. 5 is a sectional view on the line 5—5 of Fig. 3,

70 Fig. 6 is a longitudinal sectional view on the line 6—6 of Fig. 3,

Fig. 7 is a sectional view approximately on the line 7—7 of Fig. 3,

75 Fig. 8 is a perspective view of the auxiliary switch actuating lever and the elements associated therewith,

Fig. 9 is a transverse sectional view approximately on the line 9—9 of Fig. 2,

80 Fig. 10 is a detail perspective view of one of the trip members,

Fig. 11 is a detail perspective view illustrating the connection of one of the rods with one of the shafts of one of the trip members,

85 Fig. 12 is a view in diagram of the locomotive illustrating the mechanism attached thereto, parts being shown in section and locking toward the bottom of the engine,

Fig. 13 is a similar view of the end car or caboose, and

90 Fig. 14 is a sectional view approximately on the line 14—14 of Fig. 12.

Referring now to the drawings in detail, the numeral 1 designates the tracks of the main line, and 2 the tracks of the siding. 3 designates the switch rails which are arranged between the main line and siding, and the points of the switch are connected by the usual bridle rod 4, which, in the present instance, has pivotally secured thereto a rod extension 5, and the said extension has 95 its end pivotally connected with a link 6 which in turn is pivotally connected with the offset end or foot 7 of a target rod 8. The target rod is arranged in suitable bearings provided in a switch stand 9, and the said 100 rod has its end which projects above the

said switch stand provided with the usual laterally extending different colored plates which form the target 10. When the switch is thrown in one direction, it will be noted 5 that the rod 8 will be rotated to bring two of its target arms transversely of the track, these arms being each of a similar color, and also that when the switch is thrown in an opposite direction, the second pair of target 10 arms will be swung transversely of the track, the said second pair of arms being of a different color from that of the first mentioned target arm, and so it will, of course, be apparent to the engineer of the locomotive approaching the switch that the said switch is either in an open or a closed position. It is, of course, to be understood that if desired, at night a lantern having different colored bull's eyes may be arranged upon the rod 8 15 above its target arms and the different colored lenses of the bull's eyes will serve as an indicator for the engineer so that the position of the switch may be readily ascertained, this arrangement being common in 20 the art, an illustration thereof is not deemed necessary.

Positioned at approximately an equal distance from the switch 3 to, say the outer side of the main line and to the inner side of 30 the switch line are trip members of a similar construction, but indicated for distinction by the numerals 11 and 12, the trip member 11 being for the main line and the trip member 12 being for the siding. Each 35 of the trip members is substantially Y-shaped in elevation and the angular arms 13—13 of the said Y-shaped members have upon one of their faces laterally extending offset portions or flanges 14—14. The connecting member for the angular portions of 40 the Y-shaped clips have each secured thereto a shaft 15, the said shafts extending below the rails of the main line and journaled in suitable bearings 16—16 which may be secured 45 to the underfaces of the rails or to the sides of certain of the ties upon which the rails rest. Each of the shafts 15 extends beyond the rail adjacent the switch stand of the main line, the said ends being formed 50 with angular extensions 17—17 to receive each, one of the offset ends of rods 18 and 19, which are arranged longitudinally of the main track 1.

Pivotedly secured, as at 20, to one of the 55 ties which project beyond the inner rail of the main line opposite the switch 3, is a flat plate 21, the said plate resting upon at least two of the ties. The free end of the plate is preferably provided with an elongated slot 22 60 which is arranged concentric of the pivot 20, and this end of said plate is preferably covered by a flanged plate or housing 23, a pin 24 passing through the housing and through the slot 22 in the said plate 21. The plate 65 21 which, for convenience, will hereinafter

be referred to as a rest plate, has arranged upon its upper face adjacent its pivoted end vertically extending stop members 25 and 26 respectively, the same being disposed in angular relation to each other and adapted 70 one to at all times contact with one of the edges of an arm 27 which is approximately centrally pivoted to the rest plate 21, as indicated by the numeral 28. One of the ends, which may be termed the inner end of the 75 pivoted arm 27 has connected thereto the offset end of the rod 19, and the second end of said arm has loosely arranged thereon a link 29, the said link being in turn pivotally secured to the longer arm of an L-shaped lever 30, and this lever is pivotally secured 80 preferably at the juncture of its angular arms to the rest plate 21, as indicated by the numeral 31. The pivot 31 also serves as a connecting member for a flat bracket 32, and the said bracket has one of its ends connected to a link 33 which is pivotally secured to the arm 27 adjacent the pivotal connection of the rod 19 with the said arm 27. The bracket member 32 is approximately centrally connected by the pivot 31 to the rest plate 21 85 and its end, opposite that to which the link 33 is connected, is formed with an upstruck lip 34. Also the longer arm of the L-shaped lever 30 has its end formed with an upstruck 90 lip 35. The lips 34 and 35 have arranged thereon a longitudinal adjustable member 36 the said members 36 being connected with the opposite ends of a helical spring 37. The 95 spring 37 is arranged to normally swing the lipped ends of the L-shaped lever 30 and the bracket 32 toward each other for a purpose 100 which will presently be set forth.

The rod 18, which is connected to the shaft 15 of the trip 11 has its free end loosely secured to the L-shaped lever 30 adjacent the pivotal connection of the link 29 to the said lever.

The shorter arm of the L-shaped lever 30 has pivotally secured thereto, as at 39, a 110 bracket 40 which is secured to the extension 5 of the bridle rod 4. It will thus be noted that when one of the trip members, say the trip 12, is contacted (in a manner presently to be described) the shaft 15 of the said trip will be turned and the rod 18 will be moved longitudinally, thus swinging the arm 27 115 upon its pivot 28, and likewise, through the link connection between the L-shaped lever and the said arm as well as the link connection between the bracket 32 and the said arm 27, both of the rods 18 and 19 will be moved in unison and the switch thrown.

It will be noted that when one of the Y-shaped or angular arms of either of the trip members is contacted to swing the same to a horizontal position, the second arm of either of the said members will be arranged in a vertical position, or in a position to be again contacted to operate the switch, as will, it 125 130

is thought, be understood. The throwing of the switch actuates the target 10, but the said target may be moved or swung without interfering with the trip members, as will hereinafter be more fully set forth.

Secured to the rest plate 21 adjacent the non-pivoted or sliding end thereof is an offset or angular end 41 of a member 42, the end of said member extending approximately centrally over the tie upon which the switch stand 9 is arranged, but terminating a suitable distance away from said stand, and the free end of the member 42 is formed or otherwise provided with an offset socket 43, through which passes for slidable movement, a substantially rectangular arm 44, the said arm 44 entering the switch stand and being pivotally connected to the offset end 45 of a vertical shaft 46 which is arranged in bearings in the switch stand. The upper end of the shaft 46 has secured thereto an angular arm 47, and the said arm has its free end bifurcated and pivotally secured within the said bifurcation, as at 48, 25 is lever 49. The top of the switch stand has a projecting edge which is curved and provided, adjacent its ends, with notches 50, either of said notches adapted to receive the lever 49 after the same is employed for 30 rotating the shaft 46 and for normally holding the switch either open or closed to the main line, should it be found desirable to operate the said switch by the said lever. The numeral 51 designates a second or 35 auxiliary operating lever which is pivoted, adjacent one of its ends, as at 52, to the member 42, while its lower end is pivotally connected to the arm 44. The switch stand construction permits of the switch being 40 actuated by hand. The auxiliary lever 51 being pivoted to the arm 44 away from its pivotal connection 52 with the member 41 through the medium of the socket 43 permits of the sliding of the said member 42 45 when the said lever 41 is swung in either direction, such movement swinging the rest plate 21 upon its pivot 20 and through the connection between the said rest plate, the bridle rod 4 will swing the switch points 3, 50 at the same time, through the medium of the link 6 connected with the offset end of the target rod will simultaneously turn the said target rod, consequently turning the target arms. The switch points 3 may be 55 also directly operated by the turning of the shaft 46 of the switch stand through the manipulation of the lever 49. The lever 49 is swung in a line with the arm 48 and is turned upon the switch stand. The offset 60 end 45 of the lever 46 influences the arm 44 and which arm, through the medium of its pivotal connection with the auxiliary lever 51 will swing the said lever upon its pivot 52 in the direction of the member 42. This 65 provides a rigid connection between the lever

51, the arm 44 and the member 42, causing these members to move in unison and consequently swing the plate 21 upon its pivot 20 and throw the switch points 3 and the target arms 10. The spring 37 holds the 70 parts associated with the rest plate 21 in their normal condition when the switch points and target are operated from the switch stand as will, it is thought, be readily understood.

The numeral 53 designates a locomotive which draws a train of cars and the end car or caboose, indicated by the numeral 54, together with the locomotive, is provided with mechanism each of a similar construction for actuating the trip members 11 and 12. While the actuating or contact mechanism upon the locomotive and end car or caboose is, as stated, of a similar construction and will be referred to by like designating characters, it is to be stated that the projecting contact rod of the engine is adapted to be extended or projected in the side of said engine from one side of the engine which is opposite the side upon which the 90 contact rod of the caboose or end car is projected, so that when one of the trip members is contacted by the contact member of the car, the said trip member will not again be contacted by the member upon the said 95 last car of the train, but the next or second trip member will be actuated by the mentioned contact member upon the last car to return the same to its initial position.

Arranged within the cab of the locomotive 100 and at a suitable point in the last car or caboose, is a lever 55, the same being connected with a transverse shaft 56 which is journaled in suitable bearings 57 upon the underframe of the vehicle, and the said shaft 105 has one of its ends provided with an offset or flanged extension 58 which connects the longitudinally extending rod 59. This rod has its free end secured to one of the arms of a bell-crank lever 60, the second arm of 110 the said bell crank lever being secured to a strap or link 61 which has its end secured to a transversely extending contact member or rod 62, the said contact member being journaled in suitable bearings 63 and one 115 of the bearings may have a closed end or the connection between the strap and the said contact member may be so arranged as to engage with one of the bearings to prevent the lateral sliding movement of the 120 contact member 62 in one direction, so that the same will be projected from only one side of the vehicle, for a purpose previously described. The shaft 56 is provided with an angular extension 64 to which is connected a 125 rod 65 having a pivotal connection with one of the arms of a bell crank lever 66, and to the second arm of the said bell crank lever is secured a rod 67 that is connected with or may form a part of a rod 68, the latter 130

being pivotally connected with a bell crank or angular lever 69 that is pivotally secured, as at 70, to the underface of the caboose 54, the said lever 69 being connected with a rod 59 upon the said caboose.

The spring 30 serves as a means for holding one of the switch points 3 at all times in proper contact with the rail of the main line with which it is adapted to engage, retaining the rocker arm 27 in tight engagement with one of the angularly disposed stop members 25 or 26, and from the foregoing, when taken in connection with the drawings, the construction and operation of the device will, it is thought, be apparent without further detailed description.

Having thus described the invention, what we claim is:

1. In combination, a main line and a siding, a switch between the main line and siding, a pivoted plate, a connection between the plate and switch, trip members disposed to the opposite sides of the plate, an operating rod for each of the trip members, and means comprising spring influenced mechanism pivotally connected with the plate and connected with the said rods, whereby to actuate such mechanism upon the operation of either of the trip members to throw and retain the switch to one position, and for returning and holding the switch in its initial position when the second trip member is actuated.

2. In combination, a main line, a siding, and switch between the said main line and siding, of a pivoted rest plate arranged adjacent the switch, a pivoted rocker arm upon the rest plate, stop members upon the rest plate for limiting the swinging of the arm in two directions, an L-shaped lever pivoted to the rest plate, a link connection between the lever and rocker arm, a bracket pivotally secured to the lever, a tension element between the lever and bracket, a link connection between the bracket and rocker arm, rods connected respectively to the rocker arm and to the L-shaped lever and extending in opposite directions therefrom, laterally arranged shafts having offset ends connected with the respective rods, trip members upon each of the shafts, and a connection between the bridle rod of the switch and the L-shaped lever.

3. In combination, a main line, a siding, and a switch between the main line and the siding, of a pivoted rest plate, two swinging members upon the rest plate, a link connection between the members, a connection between one of the members and the bridle rod, a swinging bracket upon the last mentioned member, a tension spring between the said last mentioned member and bracket, a link connection between the bracket and the first mentioned member, means upon the rest plate for limiting the swinging movement

of the first mentioned member in two directions, a rod for each of the swinging members extending in opposite directions therefrom, trip members for the main and side lines, and each of said trip members having a connection with each of the mentioned rods.

4. In combination, a main line, a siding, and a switch between the main line and siding, of a pivoted rest plate adjacent the switch, a housing for the free end of the rest plate, angular stop members for the pivoted end of the rest plate, a centrally pivoted arm upon the rest plate adapted to be contacted by the stop members thereof, an L-shaped lever pivoted to the rest plate, a swinging bracket upon the lever, a link connection between the lever and the arm, a link connection between the bracket and the arm, means for swinging the bracket upon the arm to force the arm to engage with one of the stop members, a pivotal connection between the L-shaped lever and the bridle rod, a trip disposed to each side of the switch, connecting rods between the lever and arm of the trip members, means, comprising mechanism operative from a moving body for throwing the switch in one direction when contacting with one of the trip members for throwing the switch to its initial position when contacting the second switch to return the said second switch member to its initial position.

5. In combination, a main line, a siding, and a switch between the main line and siding, of substantially V-shaped trip members secured upon transverse shafts arranged one to each side of the switch, rods for the shafts, mechanism connected with the rods and with the bridle rod of the switch for swinging the switch when either of the trip members is contacted, and means for actuating the switch independent of the trip members and without interfering with the position of the said trip members.

6. In combination, a main line, a siding, and a switch between the main line and siding, of a shaft journaled in bearings disposed to each side of the switch, a trip member comprising a substantially Y-shaped element secured upon each of the shafts, the angular arms of each of the trips having lateral extensions, said clips being arranged in a straight line with each other, the shafts having their free ends offset, a rod pivoted to each of the said ends, swinging members connected one with each of the said rods, a link connection between the swinging members, a pivoted spring controlled element upon one of the said swinging members, a link connection between the said elements and the other swinging member, means for limiting the swinging movement of the last mentioned member in two directions.

tions, and a connection between one of the said swinging members and the bridle rod of the switch.

7. In combination, a main line, a siding, 5 and a switch between the main line and siding, of substantially Y-shaped trip members arranged adjacent one of the rails of the main line and positioned each a substantially equal distance from the opposite sides 10 of the switch, means, comprising mechanism connected with the trip members and with the bridle rod of the switch for throwing the switch when either of the said switch members are contacted, and means comprising

laterally movable rods arranged upon the 15 front and rear ends of the vehicle for successively contacting both of the trip members to throw the switch in one direction and to return the switch to its initial position.

20 In testimony whereof we affix our signatures in presence of two witnesses.
